UNITED STATES PATENT OFFICE.

ARTHUR E. ENGLAND, OF DETROIT, MICHIGAN.

THERMOSTATIC CONTROL FOR CARBURETERS.

1,208,112.

Specification of Letters Patent. Patented Dec. 12, 1916.

Application filed February 11, 1915. Serial No. 7,507.

To all whom it may concern:

Be it known that I, ARTHUR E. ENGLAND, a citizen of the United States, residing at Detroit, county of Wayne, State of Michigan, have invented a certain new and useful Improvement in Thermostatic Control for Carbureters, and declare the following to be a full, clear, and exact description of the same, such as will enable others skilled in the art to which it pertains to make and use the same, reference being had to the accompanying drawings, which form a part of this specification.

This invention relates to a thermostatic control of the needle valve of a carbureter. It is intended as an improvement on my previous application which covers broadly means for utilizing the engine cooling water to stimulate the action of the thermostatic member.

In my present invention the thermostatic element is quite differently located with respect to the carbureter and operates in a different manner than in the structure of my previous application. This will more fully appear in the description following.

In the drawings,—Figure 1 is a side view of the carbureter, the float chamber being broken away to show the interior construction. Fig. 2 is a vertical section through the carbureter and the thermostatic member.

The carbureter shell is designated *a*, the auxiliary air valve *b*, the main air gate *c*, the throttle valve *d*, the fuel nozzle *e*, the needle valve *f*, the float *g* and the float valve *h*. These are standard construction and as they are no particular part of my invention further description is not required.

The coil spring *i* bearing against the collar *j* on the end of the needle valve tends to pull the point of the needle out of the orifice in the nozzle *e*, or in other words to open the needle valve to full position. This is counteracted by the action of the rocker bar *k* pivoted to the lower end of the thermostatic bracket *l*. This thermostatic bracket is screwed to the carbureter shell by the screws shown in Fig. 1 and the thermostatic tube *m* is held to the thermostatic bracket *l* by means of the clips *n* and *o*. The clip *n* has a tight while the clip *o* has a loose fit. The engine cooling water enters through the lower nipple *p*, travels up through the tube

and out the elbow *q*. The tube is preferably a brass tube which has a high coefficient of 55 expansibility.

The operation is as follows: When the engine has been standing without working, the engine water of course becomes cool and the thermostatic tube is contracted, opening up 60 the needle valve so that a full jet of fuel can issue through the nozzle. It is at this time when the engine is cool that starting is hard and a rich mixture is required. As soon as the engine heats up the water is 65 heated and this heat is immediately conveyed to the thermostatic tube which expands, depressing one end of the rocker *r* and raising the other end. The raising of the latter end of the rocker arm causes the 70 needle valve to approach its seat and reduces the fuel jet to a point sufficient to give an adequate amount of fuel for the work, but restricting the initial amount which is now not required. It will be seen, therefore, that 75 the thermostatic member adjusts the needle valve automatically so as to care for the engine's needs. The thermostatic member also automatically takes care of the larger fuel needs of starting in cold weather, for 80 the reason that there is a greater contraction of the thermostatic member in cold weather, as the engine water is of course colder from standing in cold weather. The thermostat also adjusts itself to the precise fuel needs of 85 the engine when heated up, whether the weather is hot or cold, as it is apparent that the engine heat rather than the heat of the weather adjusts the fuel supply after the engine is set in operation.

One of the improved features of the present invention is the use of the rocker arm which multiplies the movement of the thermostatic member that is communicated to the needle valve. Any ratio of multiplication can be used by changing the length of the rocker bar on either side of the pivot. In the drawings, it will be seen that from the point where the thermostatic tube contacts the rocker bar to the fulcrum point of 95 the rocker bar, is less than one-half the distance from the fulcrum point to the set screw on the other end of the rocker bar which contacts with the needle valve. Consequently the movement of the thermostatic tube is practically multiplied by two and 100 105

one half when communicated to the needle valve. Inasmuch as the expansion of a thermostatic member is rather small, being in the thousandths of an inch, it is apparent that this multiplication secures a greater variation in the movement of the needle valve than would otherwise be possible.

The set screw *r* is for the purpose of adjusting the thermostatic apparatus and the needle valve to the needs of the particular engine upon which it is mounted.

What I claim is:—

1. In a device of the character described, the combination of a carbureter shell, a needle valve normally tending away from the needle valve seat, a thermostatic tube secured to the shell of the carbureter in substantially parallel relation with the needle valve and arranged for connection with the water circulating system of the engine jackets, and a rocker arm pivotally supported on the shell and having one end with a thrust engagement with the needle valve and the other end with a thrust engagement with

the thermostatic tube, substantially as described.

2. In a device of the character described, the combination of a carbureter shell, a needle valve, a spring normally tending to unseat the needle valve, a thermostatic tube secured at one end by a tight clip to the carbureter shell and arranged for connection with the water circulating system of the engine so as to allow the water to flow through the tube, and a rocker arm pivoted to the shell and at one end having a thrust connection with the outer end of the needle valve and at the other end having a thrust connection with the end of the thermostatic tube opposite the end which is secured to the carbureter shell.

In testimony whereof, I sign this specification in the presence of two witnesses.

ARTHUR E. ENGLAND.
